ABSTRACT OF THE DISCLOSURE

The invention is concerned with a carpet fastener of the kind comprising a metal plate from which there are pressed out, carpet engaging prongs. The invention is characterised by the shaping which is applied to the prongs.

This invention relates to carpet fasteners.

Carpet fasteners are known which comprise a strip of wood, adapted to be secured to the floors by screws or nails, there being a plurality of inclined carpet engaging prongs projecting upwardly from an upper face of the strip.

Such a device is adapted to be secured to a floor parallel to a wall (or skirting board) so as to leave a small gully between the strip and the wall. The edge of the carpet is pressed into this gully, which is adjusted to have a width slightly less than the thickness of the carpet, and when the carpet is stretched a band of the carpet inside but adjacent to this edge is impaled on the prongs which are inclined towards the wall.

Such a device is suitable for carpets having separate underlays since the vertical thickness of the wooden strip approximates to the thickness of the underlay which may, for example, be felt, and the underlay is laid up to the edge of the wooden strip so that when the carpet is laid over the underlay, the under surface of the carpet is approximately at the level of the upper surface of the wooden strip.

It will be readily comprehended that such a device is not suitable for carpets which are laid without an underlay or which have integral underlays for example, rubber backed carpets. The reason for this is that when such a strip is used in these circumstances, when the carpet is affixed to the strip, the tread of the carpet will be raised at its edge relative to its remaining tread surface, by a height corresponding to the vertical thickness of the strip, this preventing furniture or the like being positioned closely against the wall of the room adjacent to which the strip is laid.

There has previously been proposed a carpet fastener in the form of a flat metal plate, having upstanding prongs pressed out therefrom. However, in the previous proposals for carpet fasteners of this type, the prongs have been shaped to have sharp points extending horizontally, that is to say, generally parallel to the plane of the upper surface of the plate and where these prongs are located adjacent to a wall, the plate is affixed to the floor with its prong directed generally horizontally towards the wall. With such a fastener it is often difficult to ensure that the carpet is properly engaged with the prongs.

Moreover such a fastener is completely unsuitable for carpets having integral underlays. Such carpets are coming increasingly into use and in general comprise a base fabric or backing, usually of hessian, having interlaced cords, known as "wires" around which the pile elements are laid. To the underside of the backing is bonded an integral underlay in the form of a sheet, which may be

2

cellular, of a semi-rigid or elastic material. This last material is often foam material, either rubber or rubber-like material which is elastic, or in cases where the sheet is cellular or of waffle form, the material is of a more rigid nature. It will be appreciated therefore that to ensure that a carpet is properly affixed by the fastener it is necessary that the prongs of the fastener penetrate through the integral underlay and engage the wires of the base fabric or backing. However, in the case of a fastener whose carpet engaging prongs have their points directed generally horizontally, that is generally parallel to the plane of the upper surface of the plate, it is firstly difficult to ensure that the prongs engage the wires of the backing and secondly it is difficult to obtain engagement of the prongs using only finger pressure. In this last respect it must be recalled that the prongs are, in use, located closely adjacent a wall or skirting board where it is difficult to exert pressure in any case. A further disadvantage, which arises from the horizontally directed points, particularly in connection with carpets having integral underlays, is that even when the extreme tips of the points have been successfully engaged with the underside of the carpet, the carpet is moved a considerable distance laterally as the prongs penetrate further until they are buried in the carpet down to their roots.

Hence these disadvantages render it extremely difficult to obtain a practically effective and aesthetically pleasing fit of the carpet edge against a wall or skirting board and particularly in cases of carpets with integral underlays it is difficult to ensure that the carpet engaging prongs properly engage the carpet wires.

The present invention is intended to provide a carpet gripper in which the above disadvantage is obviated and which is eminently suitable for fixing carpets with integral underlays.

According to the present invention, there is provided a carpet fastener of the kind adapted to be attached to the floor, and consisting of a metal base plate having pressed out therefrom at least one row of carpet engaging prongs, the prongs of the row standing substantially at right angles to the plate when viewed transversely of the line of the row, and being so shaped that, when viewed from their sides, that is in the direction along the row, the prongs have sharp points directed upwardly substantially at right angles to the plate, the part of each prong between its point and its root being downwardly inclined at an oblique angle relative to the plate, again when viewed from the side of the prong.

In this way, the carpet fastener may be fixed to the floor adjacent a wall with the inclined parts of the prongs being directed towards the wall and so that the points of its prongs are spaced a few millimetres from the edge of the floor and when the edge of the carpet is laid over the prongs, these, being upwardly pointed, impale the backing of the carpet upon more finger pressure being exerted to press the carpet downwardly on to the prongs. The upwardly directed pointed part of each prong is arranged to be sharp so that upon mere finger pressure being exerted as described above, the upwardly directed pointed part of the prongs is fully buried in the carpet underlay. Consequently, as soon as the carpet is stretched, the carpet is pulled against the inclination of the prongs so that it slides further down the inclined parts of the prongs and moves a small distance laterally away from the edge of the floor.

Preferably the prongs are of substantially constant thickness between their points and their roots when viewed transversely of the line of the row of prongs, and hence the hole of the entry although it may be lengthened, is not widened as the carpet moves down the prongs.

Preferably the plate is provided with two or more rows of prongs, the prongs of adjacent rows being staggered relative to one another.

The invention will be further described with reference to the accompanying drawings, in which:

FIGURES 1 and 2 are diagrammatic representations showing the method of employment of two known types of carpet edge fasteners,

FIGURE 3 is a similar representation showing the method of employing a carpet fastener according to the present invention,

FIGURE 4 is a plan view of one embodiment of carpet fastener according to this invention, while

FIGURE 5 is a cross-sectional view taken on the line V—V of FIGURE 4, and

FIGURES 6 and 7 are detail views to larger scale,

FIGURE 8 is a transverse cross-sectional view of a second embodiment.

Referring now to the drawings and first to FIGURES 1, 2 and 3, 1 generally represents a floor and 2 a wall or skirting board extending at right angles upwardly from the edge of the floor 1. 4 represents the backing of a carpet usually in the form of hessian, and having interlaced cords known as wires around while pile elements, some of which are shown at 5, are laid.

In FIGURE 1 there is provided a separate underlay 6 for the carpet and with this arrangement, a carpet edge fastener which has been commonly used, is shown and comprises a strip of wood 7 from the upper surface of which project upstanding inclined prongs 8. The wooden strip 7 is secured to the floor 1 by nails or screws a small distance from the edge of the floor to leave a gully 9 between the strip 7 and the wall 2. Into this gully the edge of the carpet is positioned and as soon as the carpet is stretched in the direction of arrow 10 it will be appreciated that the backing 4 will be impaled on the prongs 8 with the extreme edge of the gully of the carpet remaining in the gully 9.

However, the type of carpet fastener shown in FIGURE 1 is not suitable in cases either where there is no separate underlay 6 or where the carpet has an integral underlay 12 as is the case with the embodiments shown in FIGURES 2 and 3. The reason for this is that the strip 7 is of necessity of substantial thickness and when it is placed under a carpet, in the absence of a separate underlay or under a carpet having an integral underlay the thickness of the strip 7 will be effective to raise the upper surface of the carpet at its extreme edge above the level of the remainder of the carpet tread.

In FIGURE 2 there is shown a carpet fastener of known type which comprises a flat metal plate 11 having upstanding prongs 13 pressed out therefrom. However, with this known type of carpet fastener, the prongs 13 are shaped to have sharp points extending substantially horizontally, that is to say, generally parallel to the plane of the upper surface of the plate 11.

With the type of fastener shown in FIGURE 2, it is extremely difficult to ensure that the prongs 13 which upstand from the plate 11, penetrate through the integral underlay 12 and into the backing 4. In particular, because of the close proximity of the tips of the points to the wall 2 and also because the points are directed towards the wall 2, it is difficult to exert sufficient pressure with the fingers alone to cause the prongs 13 to engage with the wires of the backing 4. Even in cases where it is possible to cause the prongs to penetrate the underlay 12, it is difficult to ensure that the prongs engage with the wires of the backing 4. Also it is important to ensure that the prongs initially penetrate the underlay 12 over a distance from the edge of the carpet which is substantially equal to the distance between the base of the prongs and the wall 2. Unless the carpet is correctly fitted in this respect, its edge will not be laid against the wall 2. On the other hand, to ensure a practically effective fitting for the carpet, it is advantageous to have the carpet secured as near

to the wall 2 as possible and this involves the prongs 13 being disposed near to the wall 2.

Referring now to FIGURES 3 to 6, the carpet fastener according to the present invention consists of a metal base plate 20 having pressed out therefrom at least one row 25 of carpet engaging prongs 21 which when viewed in the direction of arrow A in FIGURE 4, that is transversely of the line of the row 25, upstands substantially at right angles from the upper surface of the plate 20. Moreover, when viewed from the direction of arrow A each prong is of substantially constant thickness from its tip to its root. However, when viewed from the direction of the arrow B, that is along the line of the row 25 of prongs, the prongs are shaped as shown in FIGURE 5, with the prongs 21 having sharp pointed tips 21a directed upwardly substantially at right angles to the upper surface of the plate 20 and as can be seen more clearly from FIGURE 6, each prong has an inclined part 21b disposed between its pointed tip 21a and its root 21c.

FIGURE 6 illustrates the prongs as first cut out from the plate 20 and before being bent upwardly at right angles to the plate.

In the embodiment shown in FIGURES 4 and 5, two such rows 25 of pressed out prongs are provided on the plate 20 with the prongs of the two rows being staggered in relation to one another.

Reverting now to FIGURE 3, a carpet fastener according to this invention is shown fixed to the floor 1 adjacent wall 2 and it will be seen that with the type of fastener as now proposed, engagement of the carpet backing with the prongs will be considerably facilitated. Because the prongs have sharp upstanding points, even if the prongs are located quite close to the wall, it is possible to impale the underlay of the carpet merely using finger pressure. Provided that the points 21a of the prongs are fully impaled in the underlay, as soon as the carpet is stretched in the direction of the arrow 10, the underlay will move down the inclined part 21b of the prongs and the stretching force alone will cause the prongs to be impaled deeper into the carpet passing completely through the underlay 12 and into the backing 4. Again with the type of carpet fastener proposed according to this invention, it is necessary to ensure that the points of the prongs first penetrate the underlay over a distance from the edge of the carpet which is substantially equal to the distance between the base of the prongs and the wall. However, when the prongs have points which are directed upwardly substantially at right angles from the upper surface of the plate, it is much easier for the fitter to ensure that the prongs enter the underlay correctly.

Referring now to FIGURE 7, each prong is formed in three stages, the first two of which comprise pressing or cutting out with a suitable tool the areas X and Y to leave the shaped prong 21. The third stage comprises pressing out the prong 21 at right angles to the plate, the prong being bent substantially about the region indicated at PZ to leave an otherwise circular aperture in the plate 20. By this method the amount of metal removed from the plate 20 which is consistent with the prongs being properly and readily shaped, is kept as low as possible. This is desirable since, in many cases, the plate is required to adhere to the floor, and adhesion is best obtained if the area of the plate in contact with the floor is large as possible.

The invention is also applicable to carpet fasteners of the flanged type such as are often employed in doorways. More specifically one known embodiment of flanged carpet fastener comprises a longitudinally extending base section and a longitudinally extending clamp flange formed integrally on one edge of the base section. Commonly such a flange is inclined and overhangs the said base section. The base section is formed with upstanding prongs which are inclined towards the flange. In use, after the base section has been secured to the floor, the edge of the carpet is trimmed to length and then engaged with the prongs, whereafter in the case of an overhanging flange

the said flange is bent downwardly to bear on the edge of the carpet and this is effective to secure the carpet edge on the prongs.

However, with carpet fasteners having a base section with prongs inclined towards a flange upstanding from one edge of the base section, the correct engagement of the carpet with the prongs presents difficulties for similar reasons as have been set out above with reference to FIGURES 1 and 2.

If, however, the flanged fastener is constructed for example, as shown in FIGURE 8 of the accompanying drawings, a worthwhile improvement is effected. In FIGURE 8 the fastener has a longitudinally extending base section 81 from which are pressed out, preferably by the same method as described with reference to FIGURE 7, upstanding prongs 82. The prongs 82 although generally inclined towards a longitudinally extending flange 83 formed at one edge of the base section 81, have their extreme points directed vertically, that is substantially at right angles to the upper surface of the base section 81. By this measure initial engagement of the carpet with the prongs is facilitated, while full engagement will occur when the carpet is stretched in the direction of arrow 84 since the carpet will then be caused to slide down the inclined leading edges of the prongs so that it is progressively more completely impaled on the prongs.

Furthermore, the invention is applicable to the double flanged type of carpet fastener where in a longitudinally extending vertical rib projecting upwardly from the base plate of the carpet fastener, there being formed at least one row of carpet engaging prongs on each side of the opposite sides of the said rib.

By the present invention an improved carpet fastener is obtained.

I claim:

1. A carpet fastener of the kind adapted to be attached

to the floor, and consisting of a metal base plate having pressed out therefrom at least one row of carpet engaging prongs, the prongs of the row standing substantially at right angles to the plate when viewed transversely of the line of the row and being so shaped that when viewed from their sides, that is in the direction along the row, the prongs have a first portion extending generally vertically upwardly at substantially a right angle to said plate, a second intermediate portion extending obliquely from said first portion for ensuring full engagement of a carpet with said prongs when the carpet is stretched and a third portion extending substantially vertically from said second portion generally parallel to said first portion for ensuring an easy and effective initial securing of a carpet to said prongs upon placing the carpet thereon, said third portion having a sharp point, each of said prongs having a substantially constant thickness from their points to the plate when viewed transversely of the row of prongs.

2. A carpet fastener according to claim 1, including a longitudinally extending clamp flange formed at one edge of the base plate.

3. A carpet fastener according to claim 1, wherein a longitudinally extending vertical rib projects upwardly from the base plate of the carpet fastener, there being at least one row of carpet engaging prongs formed on each side of said rib.
